ATTORNEY.

UNITED STATES PATENT OFFICE

118,369

DESIGN FOR AN ASHTRAY OR SIMILAR ARTICLE

Ernest W. Ekstrand, Los Angeles, Calif.

Application May 8, 1939, Serial No. 84,874

Term of patent 7 years

To all whom it may concern:

Be it known that I, Ernest W. Ekstrand, a citizen of the United States, residing at Los Angeles, county of Los Angeles, in the State of California, have invented a new, original, and ornamental Design for an Ashtray or Similar Article, of which the following is a specification, reference being had to the accompanying drawing, forming part thereof.

The figure is a perspective view of an ashtray or similar article, showing my new design.

I claim:

The ornamental design for an ashtray or similar article, substantially as shown.

ERNEST W. EKSTRAND.
